COMBINED TYPEWRITING AND COMPUTING MACHINE

Henry L. Pitman, Melbourne, Fla., assignor to
Underwood Corporation, a corporation of
Delaware

Continuation of application Serial No. 343,117,
June 29, 1940. This application July 10, 1943,
Serial No. 494,434

15 Claims. (Cl. 235—69)

1

This application is a continuation of my earlier filed application Serial No. 343,117, now abandoned, filed June 29, 1940.

The invention relates to accounting machines and deal with multiple-register mechanism. More particularly, the invention deals with multiple-register mechanism for a combined typewriting and computing machine of the Underwood-Hanson class exemplified in my U. S. Patent No. 2,192,365, dated March 5, 1940.

In that class of machine, a typewriter unit surmounts and is cooperative with a computing-base. A plurality of individual computing-wheel sets or registers, and sets of indexable actuators therefor, are distributed laterally within the computing-base. The actuators are indexed for a given amount through operation of numeral keys in the typewriter and are selected for indexing under control of the typewriter carriage when the latter traverses a computing zone at operation of the keys. A general operator is subsequently cycled to drive the indexed actuators to run the indexed amount into the computing wheels.

The general object of the invention is to provide an improved combined typewriting and computing machine.

Another object resides in providing a machine of the Underwood-Hanson class which, as compared with prior machines of this class having a given number of registers, has a materially lesser number of mechanisms cooperative with these registers and accomplishes this vast reduction of operating parts without in any way curtailing the flexibility of the machine in its application to the various computing problems.

A further object is to increase the number of registers or computing-wheel sets in the computing-base, substantially without increasing the dimensions of the base.

Another object is to increase the number of computing wheel sets by contriving that the actuators, and other devices, serve for a plurality of sets of wheels instead of merely serving, as heretofore, for only one set of wheels.

A further object is to materially increase the number of registers or computing wheel sets, in a machine of the kind shown in my prior Patent No. 2,192,365 affording the salient features of adaptability to the many computing problems. Among these features is the capability of the machine of registering overdrafts or negative totals in the computing wheels and of automatically typing the true overdraft totals as instituted by the computing wheels.

Another object is to have the lateral register- 55

2

selecting shifts of the group or groups of inter-spersed registers determined automatically under control of the typewriter carriage in respect to different computing zones in the carriage travel.

5 Another object is to have the carriage control of the group-shifts take place in appropriate correlation, with group selection, denomination selection and state control by the carriage. In this connection, it is a further object to supplement 10 and coordinate carriage control structure as used for register selection, denomination selection and state control with carriage control structure for effecting the lateral shifts of the groups.

Another object is to effect the lateral shifts 15 of the groups by power and merely under control of the carriage so that the usual spring motor of the carriage is not overloaded. A power-drive separate from the general-operator mechanism may be provided for group-shifting the registers.

20 This separate power-drive is workable between, and therefore independently of, cycles of the general-operator mechanism. Mechanism operable for group-shifting the registers may be rendered cooperative with such separate power-drive under

25 control of the carriage so that the latter determines for a given computing zone of its travel which set of wheels of a group is to be active.

Another object is to provide for suppressing 30 group shifting of the registers while the machine is being cycled or is effective for other functions, such as total-taking. Conversely, cycling or effectiveness for other functions may be suppressed during the time that the registers are being group-shifted.

35 Another object is to provide for ready removal and replacement of a register-unit, and this is advantageous irrespective of whether the unit comprises a single register or a plurality of registers.

40 Other objects, features and advantages will hereinafter appear.

In the drawings:

Figure 1 is a side elevation of cycling-clutch mechanism.

45 Figure 2 is a cross sectional side elevation of a combined typewriting and computing machine embodying the invention.

Figure 3 is a perspective of the mechanism operable under control of the carriage for shifting the multiple-register units to select one or another register of a unit.

50 Figure 4 is a side-view diagram of mechanism relating to release of total-reading feelers.

Figure 5 is a perspective of the register-shift-

ing mechanism as operated for a register-shift different from that of Figure 3.

Figure 6 is a plan view diagram of the multiple-register-units and their shifting mechanism.

Figure 6A is a plan view diagram of lock details.

Figure 7 is a perspective showing a multiple-register unit as detached from the support that is movable to bring the registers into and out of engagement with the actuators.

Figure 8 is a perspective of carryover-trip and detent elements of the register unit.

Figure 9 is a perspective similar to Figure 7 but showing the register-unit in place on the movable support.

Figure 10 illustrates a detail of the computing pinion.

Figure 11 is a perspective illustrating the relative positions of tappets on the carriage for controlling total-taking and register-shifting.

Figures 12, 13, 14, 15 and 16 are top plan view diagrams of the multiple-register unit and its relation to different parts of the mechanism that is common to the computing wheel sets of the unit.

Figure 17 is a front elevation showing the parts of the register-unit frame separated to illustrate details.

Figure 18 is a cross-section view of a computing wheel.

Figure 19 is a perspective of supporting means for the register-shift controls that are operable by the carriage and also illustrates the disablement of said supporting means to disable operation of said controls by the carriage.

Typewriter unit T, Figure 2, has a main frame F supporting front and rear rails 20, 21 for a carriage 22 mounting a platen 23. Numeral keys 24 are mounted on key stems 24 operatively connected at 25 to a draw-link 26 pivoted at 27 to a stationarily fulcrumed lever 28. Each lever 28 is connected by a link 29 to an operating lever 30 connected by a bell crank 31 to a numeral type bar 32. By depressing any key-stem 24, the corresponding draw-link 26 is turned counterclockwise about its pivot 27 to engage its rear end with a continuously rotating snatch roll 34. The resulting rearward stroke of draw-link 26 depresses the corresponding operating lever 30 to drive the corresponding type bar 32 to print against platen 23. The terms, such as rearward, forward, leftward and rightward, as used herein are based on looking at the machine from the front. Draw-link 26 becomes disengaged from snatch roll 34 just before type bar 32 reaches the platen and therefore the described type-action parts return automatically to their normal positions following printing.

A universal-bar 36 enables any type bar 32 to actuate escapement dogs 37 relatively to an escapement-wheel 38 having a pinion-and-rack connection 39 to carriage 22. A spring-motor 40 drives the carriage in letter-feeding direction.

Typewriter unit T surmounts a computing base B, Figure 2. A plurality of sets of actuators or register bars 41 having racks 42 are distributed laterally, Figure 6, within computing base B. A set of idlers 43 is permanently in mesh with each set of racks 42.

Computing wheels 44 associated with each set of racks 42 and idlers 43 are collectively movable from the normal disengaged position, Figure 2, to engage racks 42 for addition, or idlers 43 for subtraction during advance of register bars 41.

Each register bar 41 is normally positioned so that its digital index-pins 46 are out of the path of descent of transverse pin-setting bars 47 individually operable by corresponding rock shafts 48 laterally distributed below corresponding type bar operating levers 30. When any lever 30 is depressed, a pendent rod 49 thereon engages a crank arm 50 of corresponding rock shaft 43 and rocks the latter to depress the corresponding pin-setting bar 47 through linkage 51.

The register bars 41 of any selected set are slightly advanceable in succession to bring their pins 46 under pin-setting bars 47 in coordination with the operation of numeral keys 24 and the attendant step-by-step feed of carriage 22 at a computing zone. For each computing zone, corresponding to a work-sheet column, carriage 22 is provided with a column unit 52 having a denomination-selector tooth 53 to traverse a universal set of vertical jacks 54 arranged in a row in the direction of carriage travel. At each denominational position of carriage 22 in a computing zone, the tooth 53 for that zone depresses a corresponding jack 54.

25 A set of bell cranks 55 is operatively connected to jacks 54 by connections diagrammatically represented by the dot-and-dash lines 56, Figure 2. Bell cranks 55 are on a fulcrum rod 57 and about a set of corresponding master racks 64 individually articulated as at 58 to a set of transverse blades 59 rockable about their lower edges in notched supports 60. Behind each set of register bars 41 there is a set of distributive racks 61 also articulated to blades 59 and presenting a set of couplers 35 62 pivoted to said racks 61. For each set of couplers 62, there is a shifter-plate 63 movable vertically for shifting the pivoted set of couplers, up or down, into or out of operative alignment with the set of register bars 41.

40 A group of cam plates 65, one for each set of register bars 41, are guided at their opposite side edges in upper and lower guide combs 66 included in a housing 67 which also slidably supports jacks 54 and is supported by the typewriter 45 framework. Cam plates 65 are selectively depressible by tappets 68 placed on the column units 52, each of which may have one or more of said tappets. The several cam plates 65 have operative connections, diagrammatically represented 50 by the dot-and-dash lines 69, Figure 2, to the coupler-shifter plates 63 so that depression of any cam plate 65 by a carriage tappet 68 lifts the corresponding-coupler-shifter plate 63 to bring the corresponding set of couplers 62 into operative alignment with their corresponding set 55 of register bars 41. A selected cam plate 65 is kept depressed by tappet 68 while the denomination selecting tooth 53 depresses jacks 54 serially in a computing-zone traverse of carriage 22. Thus, 60 the register bars 41 of any set connected to the jacks 54 are advanced serially to bring their pins 46 under the pin-setting bars 47.

For each set of register bars 41, there is a state 65 control bar 70, Figure 2, urged forwardly by a spring 71 but normally restrained by a latch 72. Depression of a cam plate 65 by the carriage lifts and thereby retracts a corresponding latch 72, from the state control bar 70 so that the latter moves forwardly until stopped by a secondary latch 73. An operative connection, not shown, enables the shifter plate 63, when lifted by said depression of cam plate 65, to also lift latch 72. If latch 73 is also retracted by means of a subtraction control, not shown, bar 70 moves still 70 farther forward to an extreme position. Follow-

ing the indexing of the register bars 41 of any set selected by depression of its cam plate 65 and further selected denominational by tappet 53, a general operator mechanism is cycled. During the cycle, a cross-bar 75, included in said mechanism, is reciprocated forwardly from and back to the normal Figure 2 position. Cross-bar 75 carries a pin-engaging lever 76 for each register bar. With the advance stroke of cross-bar 75, the upper arms of levers 76, backed by said cross-bar, engage those index pins 46 that were set downwardly at the indexing operation and thereby the register bars are advanced to extents depending on which pins were set in the several bars. Before any register bar 41 is picked up and advanced, a rock shaft 77, Figure 7, journaled in the computing base framework, is rocked clockwise. A coupler 78 is shiftable longitudinally of shaft 77 from a neutral position to an add position or subtract position determined respectively by the partial or full forward shift of a corresponding state-control bar 70. In its add position, coupler 78 couples an arm 80 to shaft 77; while in its subtraction position, it couples a bail 81 to shaft 77. As will be discussed more fully later, arm 80, or bail 81, when rocked clockwise by shaft 77 effect engagement of the computing wheels 44 with racks 42 or with idlers 43 before the advance of the register bars during the cycle. Before return of the register bars by cross-bar 75 during the cycle shaft 77 is rocked counterclockwise to disengage the computing wheels 44 from racks 42 or idlers 43.

When a computing wheel 44 rotates through a transfer point, it is operative as will be discussed later, to rock counterclockwise, Figure 2, a lever 83, which in turn raises the forward end of a bar 84 from latching engagement with a transverse bar 85. Bar 84 is pivotally connected to a stationarily-fulcrumed lever 86 having a lateral stud 87 in line with the pin-engaging lever 76 for the register bar of next higher denomination to said wheel 44. Upon its disengagement from transverse bar 85, the carryover bar 84 is moved forwardly by its spring 87 and thereby turns lever 86 counterclockwise, until arrested by a stop bar 88, to shift stud 87 rearwardly into the path of the lower arm of said lever 76. This determines rocking of said lever 76 relatively to the cross bar 75 to advance said next higher register bar an extra carryover step beyond the advance of cross bar 75.

A latch arm 82 is turnable counterclockwise of Figure 1 to retract it from a stud 89 on a plate 90 that is turnable about and with a transverse cycling shaft 91 journaled in the computing base framework and having a crank and pitman connection, not shown, to cross-bar 75 for reciprocating the latter. When plate 90 is latched, studs 92 thereon keep spring-pressed clutch-pawl 93, mounted on an adjacent plate 94 fixed to shaft 91, disengaged from a motor driven toothed driver 95 which normally is rotatably loose on shaft 91. Upon retracting latch arm 82, plate 90, spring pressed, is turned, with its studs 92, clockwise relatively to plate 94 to permit pawls 93 to engage driver 95 for a resulting cycle or clockwise revolution of shaft 91 together with plates 90, 94. The cycle is completed when stud 89 is intercepted by the meanwhile restored latch arm 82 to cause retraction of clutch-pawl 93 from driver 95.

In the instant machine there are, illustratively, three sets of register bars 41, Figure 6, and corresponding sets of idlers 43 and sets of the above-described carry-over parts including levers 83.

Each set of idlers 43 has an individual arbor 98 supported between a pair of upright flanking plates 99 fixed to a cross member 100 of the computing-base framework. Adjacent the inner sides of plates 99 there are a pair of plates 101 rigidly joined, Figures 7 and 9, to a tie rod 102, to a cross bar 103, and to a fulcrum rod 104 for the carry-over levers 83, to form a shiftable frame or support 105 for the computing wheels 44. Each plate 101 has a substantially horizontal slot 106 to slidably embrace idler-arbor 98 or a collar thereon. Arm 80 on shaft 77 has a slot 107 to embrace tie rod 102 of the frame. Normally, when the computing wheels 44 stand disengaged from racks 42 and idlers 43 as in Figure 2, arm 80 is upheld by an underlying stud 108, Figure 7, on an arm 109 fixed to shaft 77 and embracing coupler 78 at 110 for rocking said coupler and permitting movement thereof along shaft 77.

In response to the hereinbefore-mentioned partial forward movement of state control bar 70, coupler 78 is shifted rightwardly from the Figure 7 neutral position so that a tongue 111 thereof overlies arm 80. Therefore, when shaft 77 and coupler 78 are rocked clockwise, arm 80 will be rocked downwardly to depress frame 105 about idler-arbor 98 to mesh the computing wheels 44 with racks 42 for addition.

In response to full forward movement of state controller bar 70, coupler 78 is shifted leftwardly from the neutral Figure 7 position so that a tongue 113 thereof underlies an edge 114 of bail 81. Therefore, when shaft 77 and coupler 78 are rocked clockwise, bail 81 will be similarly rocked and being connected to frame 105 by side links 115 will move said frame rearwardly to mesh computing wheels 44 with idlers 43.

In the normal and the rightwardly-moved positions of coupler 78, its tongue 113 is within a clearance notch 116 of bail 81 so that when the coupler is rocked in these positions it will not influence bail 81. When arm 109 is rocked downwardly without rocking arm 80, the frame 105 remains upheld by side springs 117 which hold side studs 118 of said frame in abutment with an overlying edge of an anchor piece 119 fixed to the flanking plates 99, said springs being stretched between said studs and anchor piece, Figure 7.

The described connections for shifting frame 105 are substantially as shown in my U. S. Patent No. 2,091,717, dated August 31, 1937. The machine as so far described is also substantially like that disclosed in my aforesaid Patent No. 2,192,365, and the clutch mechanism, Figure 1, is substantially like that in my U. S. Patent No. 2,178,702. These patents may be referred to for further details.

The register bars 41 of each set run in a front comb bar 121, supported between flanking plates 99, and in a rear comb plate 122 supported by the framework. These comb members space the register bars laterally at, say, one-quarter inch intervals from each other. Idlers 43, carryover levers 83 and carryover bars 84 are also spaced by their supports at these intervals.

The novel multiple-register mechanism and associate features will now be described.

A set may consist of, say, eleven register bars 41. In the instant machine there are associated with each set of register bars 41 double the number of computing wheels 44, that is, two computing wheels of the same denominational order for each register bar. All said computing wheels may be evenly spaced along a common arbor 123 at intervals corresponding to one-half the register-

bar spacing. There are, therefore, two sets of computing wheels 44 for each set of register bars 41, and these two sets are interspersed and are coaxial on the common arbor 123. By shifting the entire group, comprising the two sets of wheels, laterally, one or the other set may be brought into cooperative relation with the common set of register bars 41 and idlers 43. It will be understood that the extent of the shift in either direction corresponds to the lateral spacing between the two computing wheels for a register bar.

The ends of arbor 123 are shouldered as at 124, Figure 17, to set into and against side plates 125. Gudgeons 126 having dowel-and-screw shanks 127 are threaded into the ends of arbor 123 to rigidly connect said plates 125 and arbor 123. Similarly, said plates 125 and a fulcrum rod 129, spaced above arbor 123, are rigidly connected by screw-shanked gudgeons 130. Two other rods 131, 132 are shouldered at their ends as at 133 to enter said plates 125 for support. A sub-frame is thus formed in respect to the frame formed by plates 99 and 101. Each computing wheel 44, Figure 18, comprises a pinion 44^a, and, for total reading, a disk 134, Figure 3, having notches 135 of graded depths forming a digit spiral. Disk 134 is spaced from pinion 44^a by pinion hub 136, and the hub and disk are secured rigidly together as at 137. The aggregate width of the wheel is substantially equal to the required spacing from one wheel to another. The aggregate width of all the wheels and a spacer 139, Figure 12, takes up the space between the side plates 125 but without binding the wheels so as to permit free individual rotations of the latter on arbor 123.

A detent arm 141 and a carry-trip lever 142 for each computing wheel are fulcrumed side by side on rod 129 which has stepped grooves 143, Figures 8 and 17, to fit open fulcrum slots 144, 145 in arm 141 and lever 142 respectively. Slot 145, Figure 8, has a circular portion for fitting over the larger part of rod 129 within the stepped groove but the outer portion of said slot 145 is constricted. In placing lever 142 on rod 129, the constricted portion of its slot 145 is first introduced over the smaller part of rod 129 within the stepped groove and then the larger circular portion of slot 145 is placed over the larger part of rod 129 within the stepped groove. A detent arm 141 is then put in place with its slot 144 engaging the smaller rod part within the stepped groove.

A bar 146 of U-shaped section embraces rod 131, and its flanges serve for anchoring tension springs 147, Figure 2, one spring for each of the detent arms 141 and carry-trip levers 142. The grooved rod 129 spaces the detent arms 141 and carry-trip levers 142 in pairs at intervals equal to the spacing of the computing wheels. Springs 147 for the carry-trip levers 142 normally keep the latter in abutment with rod 132 so that a cam-pointed tongue 148 on each lever 142 is in the path of a carry-over kicker pin 149 of the corresponding computing wheel. The kicker pin 149, Figure 18, is riveted to the disk 134 of its wheel. Each detent arm 141 is pressed by its spring 147 to keep its detent nose 141^a between any two adjacent teeth of the companion pinion 44^a to detain the wheel in any digital position.

Each plate 101 of the shiftable frame 105 has upper and lower open notches 151, 152, Figure 7, into which are received respectively the upper and lower gudgeons 130, 126, Figure 9, of the register unit which is designated generally by the letter R and comprises the computing wheels 44,

the detent arms 141, the carry-trip levers 142, and the frame made up of the plates 125 and their connecting cross members 123, 129, 131 and 132.

5 Each side plate 101 of frame 105 has pivoted thereto a catch hook 154 which may catch the upper gudgeon 130 of the register unit as in Figure 9 to keep the unit seated in frame 105, and which hook may be retracted as in Figure 7 for permitting removal of the unit. A spring 155 is attached to each catch hook 154 and to a stud on plate 101 and may throw to either side of the catch hook pivot to detent the catch hook yieldably in either position. Each catch hook may have a finger piece 154^a for manipulation.

The notches 151, 152 slidably support the register unit R at its gudgeons 130, 126 so that the unit is movable laterally in the frame 105 in opposite directions to bring either of its interspersed registers or sets of wheels 44 in cooperative relation with the common set of racks 42 and idlers 43 as will be evident in Figure 15. The lateral shifts of the unit also bring either of its interspersed sets of carry-trip levers 142 into cooperative relation with the common set of carry-over levers 83, as will be evident in Figure 16. When an active wheel 44 rotates, either in add or subtract direction, past the carry-over or transfer point, its kicker pin 149 passes the cam-pointed tongue 148 of the companion carry-trip lever 142 to actuate the latter and hence the lever 83 to release bar 84 to determine an extra carryover advance of the next higher register bar.

The laterally stationary bar 103 of frame 105 has a row of alternate teeth 156 and notches 157 opposite the detent arms 141. As will be seen in Figure 12, the notches 157 are always opposite whichever set of detent-arms 141 corresponds to the effectively positioned set of computing pinions 44^a so that said arms 141 of that set are free to move outwardly to permit rotation of the computing pinions 44^a. But the teeth 156 oppose or limit movement of the other or ineffectively positioned set of arms 141 and hence lock the corresponding set of pinions 44^a against rotation. The notches 157 may be also always opposite the set of effectively positioned set of carry-trip levers 142 to permit free movements of the latter.

A register-clearance-detecting bail bar 158 has 50 side arms 159 pivoted to the side plates 101 of frame 105, Figures 2, 9, 14. Said bar 158 has a row of cam-bevel-sided teeth 160 and interdental notches 161. The teeth 160 are always opposite whichever set of detent arms 141 corresponds to the effectively positioned set of pinions 44^a. Each computing pinion 44^a has two adjacent teeth recessed as at 162, Figure 10, so that when the pinion is in zero or clear position, the detent arm 141 settles more toward the center of the pinion than if the wheel stood at a non-zero position. Each detent arm 141 is thus capable of assuming either a clear position or a non-clear position. If a set of wheels is not clear so that one or more of its detent arms 141 stand at non-clear position, such arms will position bar 158 to oppose operation of a clearance indicating mechanism, bar 158 being spring-urged toward said arms 141. But if all the wheels of an active set are clear, bar 158 follows the clear position of all the corresponding detent arms 141 and therefore does not oppose operation of the clearance indicating mechanism. In the instant machine, the position of bar 158 determines whether or not a clear-sign-mechanism control element 163, Figure 2, may be depressed. The

sides of the teeth 159 are cam beveled as in Figure 14 so that any detent arm 141 that happens to be in non-clear position as at 141^a, Figure 14, when the unit R is to be laterally shifted will not interfere with the shifting, but instead may cam the bail bar 158 outwardly as the shift is made. The locking edges of teeth 159 of bar 103 are sufficiently forward of the detent arms 141 to permit any one of the latter to be in non-clear position as will be seen in Figure 12. But full outward movement of any arm 141 is still blocked by means of said teeth 156 to prevent rotation of pinion 44^a. In Figures 12 and 14 one of the arms 141 is shown in non-clear position at 141^a while the other arms are in clear positions.

Mechanism for laterally shifting the register units R automatically under control of the typewriter carriage will now be described.

An electric motor M is mounted at the back of the typewriter frame and to the left, Figures 3 and 6, of the housing 67 which contains the cam-plates 65. A speed reducing belt-and-pulley drive 164 connects the motor shaft to a countershaft 165 journaled on the typewriter frame and extending rightwardly beyond the right side of the housing 67. A pinion 166 fixed to countershaft 165 meshes with a larger gear 167 fixed to a short shaft 168 journaled in arms 169 and their bosses 170 of a bracket 171 fixed to the back of the typewriter frame by screws 172, Figure 2. A spiral cam 173 and its hub 173^a are fixed to shaft 168 and said hub and the hub of gear 167 abut arms 169 to hold shaft 168 and its cam 173 laterally stationary.

A rock shaft 174 is journaled in arms 169 and their bosses 175 and to it is fixed an arm 176 and its hub 176^a. An arm 177 and its hub 177^a are also fixed to shaft 174. Said shaft and its arms 176, 177 constitute a cam-follower structure shiftable laterally as a unit in opposite directions to place either arm in operative connection with cam 173, each arm having a cam-following roller 178. An extension 179 of arm 177, Figures 2, 3, 5 and 6, has a forked end 180 to straddle shaft 174 and also has a slot 181 for a screw 182 securing said extension to arm 177. A stud 183 in extension 179 engages in a slot 184 of an arm 185 fixed to a laterally-stationary transverse rock shaft 186 journaled in a bracket 189^a, Figure 6, and in a side wall W of the computing base framework. The forked end 180 and slot 181 of extension 179 permit the latter to be adjusted endwise to adjust the distance of stud 183 from shaft 174 and thereby regulate the extent of rocking movement of shaft 186 relatively to the fixed extent of rocking movement of shaft 174 by cam 173.

Another arm 187 fixed to shaft 186 is connected by a link 188 to a bell crank 189 turnable about a vertical pivot 190 in the top of a cross bar 191 of the computing base framework, Figures 2, 6. A pin-and-slot connection 189^a connects bell crank 189 to a transverse bar 192 supported and guided, for endwise shifts, by brackets 193 and pin-and-slot connections 194 to said brackets which are secured to bar 191 by screws 195. Plates 197 are fixed to bar 192 by screws 198 and present pairs of downturned ears 199, see also Figure 3, for engaging each register unit R at the outer faces of its pair of side plates 125. Therefore, the lateral or endwise shifts of bar 192 are imparted to the register units R. Each unit R in either of its lateral positions is shiftable independently of the other units to mesh either with racks 42 or idlers 43. Ears 199 are proportioned

to remain in contact with plates 125 irrespective of movements of the register unit R to engage said racks and idlers. With shaft 174 positioned laterally as in Figures 3 and 6 so that roller 178 of its arm 176 is above cam 173, said shaft 174 and its arms 176, 177 will become rocked clockwise to the Figure 3 position by cam 173 which rotates constantly clockwise. But with shaft 174 positioned laterally as in Figure 5 so that the roller of its arm 177 is below cam 173, said shaft 174 and arms 176, 177 will become rocked counterclockwise to the Figure 5 position by the clockwise rotation of cam 173. The opposite movements, clockwise and counterclockwise, of shaft 174 operate through the described train to shift the bar 192 and all the register units R leftwardly and rightwardly, respectively, as seen from the front of the machine. In this way, one or the other of the interspaced sets of computing wheels 44 of each unit R may be brought into cooperative relation with the common cooperable mechanism, comprising the register bars 41 and other common elements. Stud 183 in extension 179 is elongated so that it always engages the laterally-stationary arm 185 irrespective of the lateral shifts of said stud 183 with shaft 174.

A plate 200 is pivoted to bar 192 and is spring pressed to engage one or the other of its detent notches 201 with a tongue 202 fixed to stationary bar 191. This detent device yieldably holds bar 192 and the register units R in their laterally adjusted positions.

Two jacks or cam plates 204, Figures 2, 3, 5, 6, are alternatively depressible by means of the typewriter carriage 22 to effect the alternative lateral shifts of rock shaft 174. A plate 205 disposed between said plates 204 is stationary as will be discussed later and has pivoted thereto at 203 a lever 206 having opposite lateral arms 206^a. Studs 207 on said arms 206^a are on opposite faces of said lever 206 and underlie and are engaged by respective cam plates 204. A depending arm 208 of lever 206 has a circular end 208^a between and abutted by tabs 209 connected to a transverse bar 210 slidable endwise in slots 211 of guide plates 212 fixed to the sides of housing 67 which has clearance openings 213 for said bar 210. Each tab 209 is on a strip 214 having slots 215 to engage headed studs 216 on bar 210 for slidable support on the latter. A stud 217 on each strip extends through a clearance slot 218 in bar 210 and to it there is attached a spring 219 anchored to an extension of one of the studs 216, as in Figure 6. The outer end of a slot 215 of each strip abuts its stud 216 to limit the inward movement of the strip; with the strips thus stopped, their tabs 209 are spaced to abut the circular end 208^a of arm 208.

A block 222 is removably fixed to bar 210 by screws 223 and fits between arms 176, 177 for shifting said arms and their shaft 174 laterally by the endwise movements of bar 210. A lightly-spring-pressed detent, diagrammatically represented at 224, may be provided on one side of the housing 67 to engage one or another detent notch 225 in bar 210 to maintain the latter in either of its positions. The described springs 219 form yieldable connections which permit either cam plate 204 to be depressed by the carriage even though there may happen to be a stoppage in the train from the slide bar 210 to the register mechanism. For example, it may occur that roller 178 of arm 176 or 177 momentarily encounters a side of the constantly rotating cam 173 when one or another cam plate 204 is being de-

pressed to shift said arms laterally. With the lateral shift of said arms 176, 177 thus momentarily held up, the cam plate 204 nevertheless immediately may be depressed and the spring 219 yields, and subsequently completes the shift as soon as cam 173 has rotated sufficiently to permit the interfering roller to move over the periphery of cam 173.

Cam plates 204 are grouped with and are behind the cam plates 65 in housing 67 for coordinate selective operation of one or another cam plate 204 with any cam plate 65. Said cam plates 204 and their intermediate supporting plate 205 are guided vertically in the guide combs 66 of said housing 67. Plate 205 rests upon a transverse plate 230, Figure 19, that is similar to transverse plates that uphold cam plates 65 and form part of the operative connections diagrammatically represented at 69, Figure 2. Such transverse plates are shown in my aforesaid Patent No. 2,192,365. Plate 230 rests upon a rod 231, Figure 19, connected to a lever 232 having a fulcrum rod 233. An arm 232a of lever 232 abuts a fixed stop 235 and thereby, with the fulcrum rod 233 in normal position, maintains the upper plate 205 and cam plates 204 at such elevation that one or the other of the cam plates 204 is in the path of a corresponding tappet 234, Figures 2, 11, provided on one or another column unit 52 on the typewriter carriage. Fulcrum rod 233 is connected by side links 236, Figure 2, to horizontal arms 237 fixed to a rock shaft 238 which also has vertical arms 239 supporting fulcrum rod 57 for the bell cranks 55.

As soon as a cycle of the general operator, including cross bar 75, gets under way, shaft 238 is rocked clockwise to lower the rod 233 to the dotted line position, Figure 19, thereby causing plates 204, 205 to drop so that cam plates 204 are out of the path of the carriage tappets 234. Therefore, the carriage is inoperative during a cycle to cause lateral shift of the register units R. Mechanism for thus lowering the rod 233 may be as shown in my U. S. Patent No. 2,160,487 dated May 30, 1939. Such mechanism may also operate to lower said rod 233 during the usual power-return of the carriage as set forth in said patent. Therefore, the register units will not be idly shifted laterally during such carriage-return.

The machine may be equipped with automatic total-printing mechanism. For a register unit R there is a set of total-reading feelers 241, said set being common to the interspersed sets of computing wheels 44 of said unit. By shifting the register unit R laterally one or the other set of disks 134 is brought into operative alignment with the common set of feelers 241 as will be evident in Figure 13. Each feeler is urged by a spring 242, Figure 2, toward the disk 134 and normally all the feelers are held retracted in the Figure 2 position by a transverse bar 243. Said bar 243 has a connection diagrammatically represented at 244, Figure 4, to an arm 245 and its rock shaft 246 in the computing base. A stud 247 on arm 245 is normally caught by a latch arm 248 fixed to a transverse rock shaft 249 journaled in the computing base. By rocking shaft 249 and latch arm 248 clockwise, arm 245 is released for resulting movement, to the left of Figure 4, so that bar 243 recedes from feelers 241 and the latter move to engage whichever of disks 134 is in operative alignment with said feelers. Leftward movement of arm 245 by its spring 250 is limited by a stop 251. Upon de-

pression of a total key lever 252, Figure 2, carriage 22 is tabulated leftwardly toward a total-printing zone where a tappet 253 on a column unit 52 depresses a cam plate 254 which has an operative connection diagrammatically represented at 255, Figure 4, to latch arm 248 to retract the latter to release the feelers 241. The released feelers 241 assume positions, against disks 134, corresponding to the total in the active set of computing wheels 44. Correspondingly, a type selector, not shown, on each feeler 241 is positioned under one of a set of transverse blades 256, Figure 2, corresponding to the numeral type actions, for selecting the latter for ensuing total-printing operations, by snatch roll 34, under denominational control of the carriage 22.

For a fuller explanation of the total-printing mechanism, reference may be had to my aforesaid Patent No. 2,192,365. As afore indicated, the present machine, with its interspersed totalizers, is contrived to afford the advantageous features of said patent which deals with overdrafts and printing true overdraft totals. Besides ten of the blades 256, one for each digit from "0" to "9," there is an eleventh blade 256, as shown in Figure 2, for controlling the overdraft total-printing. An overdraft may be manifested in a totalizer by its highest order computing wheel standing at "9." The highest order disc 134 is arranged so that, standing at the "9" position, the corresponding feeler 241 will become positioned, with its selector, not shown but similar to selector 466 of said patent, under the eleventh blade which may be the last one toward the right of Figure 2. When the carriage is positioned at the place corresponding to the denomination of the highest order totalizer wheel, said eleventh blade 256 becomes lifted by means of such selector and, consequently, a case shift mechanism, not shown, becomes operated. A fugitive one mechanism is provided so that in the case of an overdraft it is the nines complement of the true overdraft which is registered in all the wheels of the totalizer. The type bars 32 are selected and operated according to this complement, but will print the true negative total inasmuch as the case shift mechanism has been operated and the upper case types of the type bars are the complement of the lower case types, all substantially as set forth in said Patent No. 2,192,365. It will thus be seen that the present machine is one that is capable of subtracting as well as adding in any one of the interspersed totalizers and is, moreover, capable of printing the true negative total from any interspersed totalizers that may be in overdraft condition. The present invention also provides for preventing release of the feelers 241 while the register units are being laterally shifted and, conversely, for preventing lateral shifts of the register units while the feelers are in engagement with the disks 134. Therefore, the following mechanism is provided.

An arm 257, Figure 4, fixed to shaft 249 is connected by a link 258 to an arm 259 fixed to a transverse rock shaft 260 in the computing base. An arm 261, Figures 2, 3 and 6, fixed to shaft 260 has a camming corner 262 and a dwell 263. A pusher 264 is slidably supported on shaft 249 as at 265 and is pivotally connected at 266 to an arm 267 loosely fulcrumed on a shaft 273 which also carries the clutch latch arm 82. A side stud 268 on pusher 264 is normally in the path of said camming corner 262 of arm 261.

When carriage 22 becomes tabulated to a total-printing zone upon depression of a total-key lever 252, one or the other register shifting cam plates 204 may be depressed by its tappet 234 for a resulting lateral shift of the register units R to determine which of the interspaced sets of computing wheels is to be engaged by the feelers 241.

While shaft 174 is being moved endwise and then rocked by cam 173, in either direction to effect a lateral shift of register units R, an edge 269 of an arm 270 fixed to said shaft 174 traverses one of two blocks 276 and a lateral spur 271 presented by a branch 272 of arm 267 which is connected to pusher 264. Said edge 269 thus serves to block rise of the branch 272 and thereby blocks clockwise movement of arm 261 in that the camming corner 262 of the latter is blocked at the side stud 268. The described blocking of arm 261 during register-shifting rocking movement of shaft 174 blocks feeler-releasing retraction of latch arm 248. It may be explained here that the register-shift control tappet 234 and the total-control tappet 253 are off-set, in the direction of carriage travel, on the column unit 52 as in Figure 11. This provides for timing the lateral shift of the register units to occur ahead of the release of the feelers.

The locking operation is as follows: With the shaft 174 in its rightwardly shifted and correspondingly rocked position, Figure 6, the lower blocking end 269 of arm 270 of said shaft will be in the position *a*, relatively to the spur 271 and the blocks 276, see the enlarged scale plan view diagram, Figure 6A. At the start of leftward shift of shaft 174, its blocking-arm-end 269 immediately moves leftwardly to overlie the forward block 276; and at the end of the leftward shift, said blocking end 269 may have the position *b*, whereby counterclockwise rocking of lever 267, 272 and hence rightward withdrawal of stud 268, Figure 2, from the path of arm 261 are blocked to prevent release of the feelers 241. The leftward shift of shaft 174 positions the roller of arm 177 opposite the rotary cam 173 and consequently said cam immediately rocks shaft 174 counterclockwise thereby bringing the blocking end 269 to the position *c*, Figure 6A, in which it is over the clearance afforded within the corner of spur 271 and rear block 276 and, therefore, does not oppose the lever 267, 272 but leaves the latter free to rotate counterclockwise to permit the release of the feelers 241. In later rightward endwise shift of shaft 174, its blocking-arm-end 269 moves from the position *c* to the position *d*, Figure 6A, and thereby moves over and opposes the rear block 276 to oppose release of the feelers 241 during this rightward shift. This rightward shift of shaft 174 brings the roller 178 of arm 176 again opposite cam 173 and the latter immediately rocks shaft 174 clockwise and brings its blocking end 269 back to the position *a*, Figure 6, in which position said arm-end 269 is over the clearance space afforded within the corner of the forward block 276 and the spur 271 and does not oppose release of feelers 241. It will be seen, therefore, that release of the feelers 241 is blocked during endwise and rocking movements of shaft 174 and during the corresponding arrow-indicated movements defining a four-sided or orbital path, of blocking end 269 from *a* to *b* to *c*, or from *c* to *d* to *a*, Figure 6A.

Arm 270 may have clearance corners 274 defining the ends of the locking edge 269.

In either shifted position of shaft 174, the side

of the inactive roller 178 stands at a slight space, see Figure 6, from the side of cam 173. By the time the endwise shift of shaft 174 has closed up the space, and has possibly brought the side of the inactive roller 178 to bear transiently against the side of the rotating cam 173, with attendant momentary delay of completion of the shift of shaft 174 and of shift of the registers, the blocking end 269 will be over one of the blocks 276. The locking mechanism thus becomes effective to block release of the feelers 241 even though the feeler-release cam plate 254 may have been depressed by the carriage before the endwise shift and rocking of shaft 174 have been completed.

Branch 272 and arm 270 may also interlock laterally to prevent lateral shifts of shaft 174, and hence of the register units R while the feelers 241 are in engagement with the disks 134. While the feelers are so engaged, an edge 248^a, Figure 4, of latch arm 248 may rest on top of stud 247 to keep said arm 248 in retracted position, said latch arm 248 having been retracted for resulting release and movement of arm 245 and, hence, of bar 243 so that the feelers 241 engage disks 134. This will keep dwell 263 on arm 261 opposite stud 268 to keep pusher 264 in position so that spur 271 is placed in one or the other clearance corner 274 of arm 270. In such case, one or the other of the opposite lateral sides of the lower end portion of arm 270 is opposed by the side of a corresponding one of the two blocks 276 secured to opposite, front and rear, sides of spur 271 of branch 272 and thereby lateral shift of arm 270 and hence of shaft 174 to institute lateral shift of the register units R is opposed.

An arm 277 loosely fulcrumed on shaft 273 has a side stud 279 abutting clutch-latch arm 82. Said arm 277 is connected by a yoke 280 to arm 267 which has the branch 272. Therefore when clutch-latch arm 82 is retracted to institute closing of the clutch, arm 277 is correspondingly moved to raise spur 271 into one or the other clearance corner 274 of arm 270 and therefore branch 272 and arm 270 will be in lateral interlock at one or another block 276 to oppose lateral shift of the register units R as soon as the cycle clutch is tripped. The cycling clutch cannot be tripped while shaft 174 is being shifted endwise and then rocked to laterally shift the register units R because in such case one or the other block 276 and spur 271 will be opposed by edge 269 while the shift and rocking of shaft 174 are taking place and hence side stud 279 will oppose full clutch releasing retraction of clutch latch arm 82. Said arm 82 has its latching shoulder terminating in a cam bevel 82^a. The arrangement is such that the blocking edge 269 will permit retraction of latch arm 82 just far enough to bring said cam bevel opposite stud 89 so that the latter although released from said latching shoulder cannot move far enough to determine engagement of clutch pawls 93 with the driver 95. When the rocking of shaft 174 is completed, the rise of spur 271 may be completed into one or another clearance corner 274, and at this time closing of the clutch will be completed. If it should occur that the cycling clutch is tripped substantially at the same time that one or another of the cam plates 204 is depressed, the described interlocking mechanism will constrain operation of the cycling mechanism and lateral shift of the register units R to take place in sequence instead of concurrently. For example, the spur 271 may be blocked by the edge 269 in that the shift of said units takes precedence

while the closing of the cycling clutch is held up by blocking of the cycling clutch stud 89 by the camming bevel 82a of arm 82; when the register shift is completed, however, full retraction of the latch arm 82 takes place in that said spur 271 will then be opposite one or the other clearance corner 274. In a similar way a lateral shift of the register units and full forward movement of the feelers 241 are constrained to occur in sequence by the described interlock mechanism if said feelers become released at the same time that one of the cam plates 204 is depressed.

It will be seen now that the invention provides for materially increasing the multiple-register capacity of the machine without substantially increasing the dimensions of the computing base; that any multiple-register unit is selectable automatically under control of the typewriter carriage and at the same time the carriage may also determine an automatic shift of the unit to render one or another set of computing wheels of the unit effective; and that the provisions for increasing the multiple-register capacity of the machine are readily applicable to existing designs of the Underwood-Hanson combined typewriting and computing machine.

Variations may be resorted to within the scope of the invention and portions of the improvements may be used without others.

What is claimed is:

1. The combination with a traveling carriage, two registers, a common mechanism to cooperate with one or the other register, of a power-operated rotary cam device, a cam-follower structure movable by the cam-device in one or another direction depending on one or another position of the structure relatively to the cam-device, means enabling the carriage to determine said one or another position, and means for translating the movement of the structure in one or another direction by the cam-device into corresponding movement of one or the other register into position for cooperation with the common mechanism.

2. In a computing machine, the combination with a traveling carriage, a plurality of registers, and a common mechanism cooperative with one or another register, of a plurality of register selectors selectively operable by the carriage, a motor-driven rotary cam-device, a cam-follower structure, means cooperative with the selectors to relatively shift said cam-device and structure for predetermining one or another direction of movement of the structure by the cam-device depending on which selector is operated, and means for translating the movements, in one or another direction, of the structure by the cam-device into corresponding relative shifts of the registers and said common mechanism for register selection.

3. In a computing machine, the combination with a traveling carriage, a plurality of registers, and a common mechanism cooperative with one or another register, of a plurality of register selectors selectively operable by the carriage, a motor-driven rotary cam-device, a cam-follower structure, means, including a yieldable connection, cooperative with the selectors to relatively shift said cam-device and cam-follower structure for determining one or another direction of movement of the structure by the cam-device depending on which selector is operated, said yieldable connection being operative to avoid jamming in case of occasional interference between the cam-device and structure when a selector is operated to effect their relative shift,

and means for translating the movements, in one or another direction, of the structure by the cam-device into corresponding relative shifts of the registers and said common mechanism for register selection.

4. In a computing machine having interspersed sets of register wheels and a set of actuators common to the wheel sets; register mounting structure comprising a wheel frame, including side plates, in which the laterally interspersed sets of wheels are journaled and retained against lateral displacement; an outer frame including side plates, each side plate of one of the frames having two studs, and each side plate of the other frame having two openings to receive the studs to support the wheel frame for lateral shifts relatively to the outer frame to bring selectively one or another wheel set into line with said actuators; means supporting said outer frame for movement transversely of the wheel axis to move the selected wheel set to and from the actuators; and means having an operative connection with the wheel frame for shifting the wheel frame laterally relatively to the outer frame, said connection bearing only laterally on the wheel frame so as not to impede the transverse movement of the wheel frame.

5. In a computing machine having a cycling general operator, the combination with a traveling carriage; a multiple-totalizer unit; a set of actuators common to the totalizers of the unit, said unit and actuators being relatively shiftable to different positions to select one or another totalizer for cooperation with said actuators; a device operable before a cycle for determining engagement, during the cycle, of the selected totalizer and the actuators, and a tappet on the carriage to operate said device; of operable elements, one for each of said positions; supplementary tappet-means on the carriage to operate said elements selectively before the cycle; and means immediately responsive to operation of any one of said elements to shift the unit to the position corresponding to the operated element if the unit is not in said latter position.

6. In a computing machine having a cycling general operator, the combination with a traveling carriage; two totalizers and a common mechanism with which either totalizer may cooperate by effecting opposite totalizer-selecting relative shifts of the two totalizers and said mechanism; of a selector for each totalizer; means associated with the carriage to operate the selectors selectively; a motor-driven mover capable of functioning at any time irrespective of cycling of the general operator; a mover-operable structure for relatively shifting the totalizers and mechanism, said structure being selectively positionable relatively to the mover and movable by the mover in either of opposite directions, depending on which position is selected; means controlled by the selectors to selectively position the structure relatively to the mover; and means for translating the opposite movements of said structure by the mover into corresponding relative shifts of the totalizers and said common mechanism for totalizer selection.

7. In an accounting machine having a traveling carriage, a laterally shiftable unit comprising interspersed totalizers, and a common mechanism associative with one or another totalizer as the unit is shifted; the combination of a power-operated cam, a cam-follower structure, a lever having an operative connection to said follower structure and rockable in opposite directions to

shift said structure relatively to said cam for predetermining one or another direction of movement of the structure by the cam, means for translating the movements, in one or another direction, of the structure by the cam into corresponding shifts of said unit to associate one or another totalizer with said common mechanism, and means operable by the carriage for rocking said lever selectively in one or another of said opposite directions.

8. In an accounting machine having a travelling carriage and a unit comprising interspersed totalizers laterally shiftable to associate one or another totalizer with a common cooperable mechanism, the combination of a power-operated cam, a cam-follower structure laterally shiftable relatively to the cam so as to be movable alternatively by the cam in opposite directions, means for translating the opposite movements of the structure by the cam into corresponding shifts of said unit to associate one or another totalizer with said common mechanism, two jacks, tappet means on the carriage to operate said jacks selectively, a lever having operative connections to said jacks so as to be operable in one direction and alternatively in the opposite directions by alternate operations of said jacks, and means for transmitting the operations of said lever in each direction to said follower structure for shifting said structure relatively to said cam.

9. In an accounting machine, the combination with interspersed totalizers shiftable laterally to associate one or another totalizer with common actuators, and total printing mechanism cooperable with the totalizers and operable at a different time than the totalizer shifts, of a power-operated driver, a driver-operatable member for shifting said totalizers and shiftable laterally relatively to said driver in opposite directions preparatory to operation of said member, said member being operatable by said driver in one or another totalizer-shifting direction transversely to the lateral shift of said member, the lateral shifts and transverse operations of said member occurring alternately, namely, a lateral shift in one direction and consequent transverse operation in one direction and, later, an opposite lateral shift and consequent transverse operation in opposite direction, a locking element associated with said member and arranged to move in an orbital path as the lateral shifts and transverse operations of said member occur alternately, and a blocking means associated with said total printing mechanism, said locking element and blocking means being constructed and relatively arranged so as to be in opposition to each other to block operation of said total printing mechanism while said member is being laterally shifted and transversely operated and to block lateral shift of said member while said mechanism is being operated.

10. In an accounting machine having a travelling carriage, the combination of a totalizer support, a multiple-totalizer unit mounted in said support for lateral shifts relatively to the support to place selectively one or another totalizer opposite actuators individual to the unit, means mounting said support so that it is individually movable transversely of the direction of the lateral shift of the unit to move the selectively placed totalizer of the unit to and from the actuators, a bar mounted for endwise shifts longitudinally of the totalizer unit and having operative connection with said unit for laterally shifting the unit at the endwise shifts of the

bar, said operative connection being arranged to permit the transverse movement of said unit with its support, tappet means on the carriage and mechanism selectively operable under control thereof to effect endwise shift of the bar selectively to one or another position to place one or another totalizer of the unit opposite the actuators, and tappet means on the carriage and mechanism selectively operable under control

5 thereof to transversely move the support.

11. In an accounting machine, the combination with interspersed totalizers shiftable laterally to associate one or another totalizer with common actuators, and cycling mechanism operable at a different time than the totalizer shifts, of a power-operated driver, a driver-operatable member for shifting said totalizers and shiftable laterally relatively to said driver in opposite directions preparatory to operation of said mem-

15 ber by said driver in one or another totalizer-shifting direction transversely to the lateral shift of said member, the lateral shifts and transverse operations of said member occurring alternately, namely, a lateral shift in one direction and con-
20 sequent transverse operation in one direction and, later, an opposite lateral shift and conse-
25 quent opposite transverse operation in opposite direction, a locking element associated with said member and arranged to move in an orbital path

30 as the lateral shifts and transverse operations of said member occur alternately, and a blocking means associated with said cycling mechanism, said locking element and blocking means being constructed and relatively arranged so as to be in
35 opposition to each other to block operation of said cycling mechanism while said member is being laterally shifted and transversely operated and to block lateral shift of said member while said cycling mechanism is being operated.

40 12. A computing device comprising a plurality of juxtaposed wheels for each denominational order, an actuator for each denominational order, means including a laterally shiftable sub-frame for effecting relative movement between the
45 wheels and the actuators whereby engagement of the actuators is effected selectively with a corresponding one or another of the juxtaposed wheels of each order, means, in part shiftable with said sub-frame and in part non-shiftable, for causing a tens transfer from a lower order wheel to a higher order wheel in any selected engagement and in either rotative direction of the wheels, and means for introducing a fugitive one to the device in any selected engagement.

55 13. In a credit-balance computing machine having an automatic total printing mechanism, a multiple register unit constructed and arranged to accumulate accurate positive and negative totals from the entry of add and subtract items, comprising interspersed sets of computing wheels so arranged that the wheels of the same denominational order of each set are juxtaposed and further comprising tens-transfer operating ele-
60 ments, a single set of actuators for said wheels, means for conditioning the wheels of any set for actuation by the set of actuators, including a laterally shiftable sub-frame carrying said tens-
65 transfer operating elements means for correcting the lowest order wheel of each set for a differ-
70 ence of one unit when the wheels of that set pass from a positive to a negative total or vice versa, and means associated with the automatic total printing mechanism for sensing a negative condition of any of the sets of wheels.

14. In a computing machine, a multiple register unit constructed and arranged to accumulate accurate positive and negative totals from the entry of add and subtract items, comprising interspersed sets of computing wheels so arranged that the wheels of the same denominational order of each set are juxtaposed and further comprising tens-transfer operating elements, a single set of actuators for said wheels, means for conditioning the wheels of each set for actuation by the set of actuators including a shiftable sub-frame mounting said wheels and said tens-transfer operating elements, and means for correcting the lowest order wheel of each set for a difference of one unit when the wheels of that set pass from a positive to a negative total or vice versa.

15. In a machine of the class described, a plurality of registers, said registers having their wheels mounted on a common axis and interspersed so that the wheels of the same denominational order of each register are juxtaposed, a tens-transfer operating element for each wheel of each register, a single set of actuating devices for said registers and a tens-transfer device for each actuator, means including a laterally shiftable sub-frame for effecting a relative movement between said registers and said actuating devices to bring one or another register and its appropriate tens-transfer operating elements into posi-

tion to be operated by said actuating devices, and means operable by the tens-transfer operating element of the highest order wheel of each register for effecting operation of the tens-transfer device of the lowest order actuator.
